(57) **CLAIM**

The ornamental design for a valve lever, as shown and described.

DESCRIPTION

FIG. 1 is a perspective view of a valve lever showing my new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof, with the bottom plan view being a mirror image thereof.

The evenly-spaced broken lines depict portions of the valve lever which form no part of the claimed design. The unevenly-spaced broken lines depict a boundary of the claimed portion and form no part of the claimed design.
